ELECTRIC SWITCH

Paul R. Goudy and Kenneth G. Sedgwick, Milwaukee, Wis., assignors to Square D Company, Detroit, Mich., a corporation of Michigan

Application November 17, 1951, Serial No. 256,856

17 Claims. (Cl. 200—124)

1 This invention relates to electric switches, and more particularly to electric switches manually operable at will to open and closed positions, and automatically operated to open position in response to overload currents, such as are used for the control and protection of electric motors.

One object of the present invention is to provide a manual and automatically operable electric switch having an improved and reliable operating mechanism.

Another object of the invention is to provide an improved automatic manually operated electric switch having fixed and movable contacts, the movable contacts being slidably mounted within the base, while the fixed contacts are "snapped" into position on the base to cooperate with the movable contacts.

Another object of the invention is the provision of an electric switch in accordance with the preceding object in which the fixed contacts are integral with circuit terminals.

Another object of the invention is the provision of an electric switch in accordance with the preceding objects in which an insulating cover, which is provided about the fixed contacts, is mounted to the main base by being "snapped" into position.

Another object of the present invention is the provision of an electric switch having an improved mounting arrangement for the movable and fixed contacts whereby access to these contacts may readily be had.

Other objects and features of the invention will be readily apparent to those skilled in the art from the specification and appended drawings illustrating certain preferred embodiments in which:

Figure 1 is a plan view of the electric switch according to the present invention.

Figure 2 is a sectional view along the lines II—II of Figure 1.

Figure 3 is a detail sectional view along the lines III—III of Figure 1.

Figure 4 is a sectional view along the lines IV—IV of Figure 1, the operating mechanism being shown in the "on" position, certain of the parts being broken away to facilitate this showing.

Figures 5 and 6 are views similar to Figure 4, in which the operating parts are shown in the "off" and "tripped" positions, respectively.

Figure 7 is a sectional view along the line VII—VII of Figure 1.

Figure 8 is a detail sectional view along the line VIII—VIII of Figure 1.

Figure 9 is a detail sectional view showing an intermediate step in the method of mounting the fixed contacts to the base.

Figure 10 is a rear view of the contact chamber

2 with part of the cover broken away to show internal parts.

Figure 11 is an exploded view of the operating mechanism of the present invention.

5 The electric switch, according to the present invention, comprises a molded, Bakelite base 1 to which a metal frame 3 is fixedly mounted by screws 2. The frame 3 has depending side plates 4 projecting toward the interior of the base 1.

10 A manually operated handle 5 is pivoted upon a pin extending between, and through suitable apertures in, the side plates 4.

The underside of handle 5 is provided with a slot 6 within which operates a pin 7 which is 15 fixedly mounted to the upper portion of a spring lever 8. The spring lever 8 has upper ears 9 which, when lever 8 is in mounted position, straddle opposite sides of the under portion of handle 5 within the side plates 4. The spring lever 8 is pivotally mounted within the side plates 20 4 by means of pins 11, which project outwardly from the spring lever 8, and slots 12 provided in the lower portions of the side plates 4. A tongue 13 depends from the lever 8, and is provided with a suitable hole 14 through which 25 extends one hooked end of an operating spring 15.

The opposite hooked end of the spring 15 is mounted to one end 16 of an actuating lever 30 17, which has riveted thereto an insulating extension 18. Projecting outwardly from opposite sides of the actuating lever 17, are a pair of pins 19 which are disposed within suitable slots 21 of an overload lever 22.

35 This overload lever 22 is mounted pivotally by means of a pin to the side plates 4 of the frame 3. The upper end of lever 22 is provided with ears 23 which also straddle opposite sides of the under portion of handle 5, within the side plates 4.

As may be seen more clearly from Figure 3, to the overload lever 22 there is fixedly mounted by rivets an insulating piece 23 to which, in turn, there is riveted a metal latch 24. The overload mechanism which normally holds the latch 24 in a predetermined position is mounted 45 to the base 1 by means of a screw 25, and comprises a cup 26 within which is disposed a shaft 27, the outer end of which carries a ratchet wheel 28. Within the cup 26 and disposed between its interior surface and the shaft 27 is disposed a relatively low melting point alloy in conventional manner, which in solidified condition prevents rotation of the ratchet 28. Disposed about the cup 26 is an insulating spool 29 which carries turns of a resistance heating element 31.

50 One end of the resistance heating element 31 is connected, as shown in Figure 1, to a terminal screw which is provided in a connector unit 32.

One end of the resistance heating element 31 is connected, as shown in Figure 1, to a terminal screw which is provided in a connector unit 32.

of conducting material, which is mounted to the base 1 by means of a rivet 33. The opposite end of the resistance heating element 31 is connected to a screw 36 which is provided in the upper end of a generally U-shaped terminal contact member 34.

The device of the present invention is provided with four identical terminal-contact members 34, each of which, as will readily be seen from Figure 9, comprises a generally U-shaped section of conducting material to the interior end of which there is fixedly mounted an electrical contact 35, while the upper end is provided with a threaded hole in which a terminal screw 36 operates. At opposite sides of each of these threaded holes there are provided in the terminal-contact member 34 lanced ears 37. As may be seen from Figure 8, the molded base 1 is provided with suitable slots 38 positioned so that the ears 37 fit therein when the terminal-contact members 34 are in position. Figure 9 shows that member 34 is mounted to base 1 by engaging the base 1 with the contact end of member 34, force then being applied to the terminal end of member 34 whereby ears 37 are forced inwardly toward slots 38, into which they finally move, the inherent resiliency of member 34 maintaining this position. Disposed about these terminal-contact members 34 is a U-shaped, molded Bakelite cover 39 having integrally molded, inwardly facing nubs 41. The legs of cover 39 are spaced apart a distance such that these nubs 41 force the legs to spread outwardly when cover 39 is forced to engage the base. When cover 39 has been moved to its proper position, however, the nubs 41 project over ledges 42 of the base 1, whereby the cover 39 is held in position about the terminal-contact members 34 by means of its inherent resiliency.

As may be seen in Figure 10, the interior section of the base 1 is formed into three different chambers by a pair of insulating walls 45 integral with the base 1. These walls 45 are provided with slots 46, and aligned therewith are slots 47 formed in the opposite side walls of the base 1. Within these slots 46 and 47 there is disposed a rectangular, movable contact carrier 48 of insulating material. As may be seen from Figure 7, the carrier 48 is provided with a pair of spaced openings 49 through each of which extends a double ended movable contact finger 51, a spring 52 being disposed within each of the openings 49 to bias the fingers 51 toward the position illustrated in Figure 7. The fingers 51 are of conducting material and carry at each end an electrical contact 53. Centrally disposed within the carrier 48 is another opening 54 through which projects one end of the extension 18 of the actuating lever 17.

The operation of the device will now be described. When the handle 5 is rotated in a clockwise direction from the position of Figure 4, the spring lever 8 is rotated in a generally counterclockwise direction about its pivotal connection with slot 12 by virtue of the pin 7-slot 6 connection between the spring lever 8 and the handle 5. The end of operating spring 15 connected to the spring lever 8 is thereby carried downwardly from the view of Figure 4, and the spring 15 is progressively stressed as this movement of the operating handle continues. When the movement has progressed to the position in which the lower end of the spring 15 has passed the pin 19-slot 21 connection, so that the line of force

of the spring 15 is below the point of the pivotal connection between the actuating lever 17 and the overload lever 22, spring 15 will effect a rapid pivotal motion of the parts to the position of Figure 5. It will be seen that in this position, the extension 18 of the operating lever 17 has moved the movable contact carrier 48 outwardly, whereby the movable contacts 53 are separated from the fixed contacts 35.

With the parts in the "off" position as illustrated in Figure 5, as the handle 5 is rotated in a counterclockwise direction, the spring lever 8 is carried in a generally clockwise direction about its pivot in the slot 12, carrying the end of the spring 15 attached thereto upwardly (from the view of Figure 5) until its line of force is above the pivotal connection between the actuating lever 17 and the overload lever 22. When the line of force of the spring has passed this point, spring 15 will effect a rapid pivotal motion of the actuating lever 17 about its pivot in the slot 21, the extension 18 of the actuating lever 17 carrying the movable contact carrier 48 rapidly inwardly within the slots 46 and 47 until the parts are in the position indicated in Figure 4, the movable contacts 53 bridging the fixed contacts 35.

Should an overload occur, when the overload current flows through the heating element 31, the alloy within the cup 26 melts. The force exerted upon latch 24 by the spring 15 will thereby force the latch 24 to rotate the ratchet wheel 28 and become free therefrom, the overload member 22 to which the latch 24 is mounted being rotated in a clockwise direction about its pivotal connection in the side plates 4 of the frame 3. As the pin 19-slot 21 connection is moved across the line of force of the spring 15, spring 15 will effect a clockwise rotation of actuating lever 17 about its pivotal engagement in the slot 12 until it reaches the position shown in Figure 6. In thus moving, the upper end 16 of the actuator 17 has moved below the pivot 11-slot 12 connection between the spring lever 8 and the frame 3. In this position the spring 15 forces the tongue 13 of spring lever 8 to move downwardly from the position shown in Figure 4 to the position shown in Figure 6, rotating the spring lever 8 counterclockwise about its pivotal connection with frame 3 and by virtue of the pin 7-slot 6 connection with the handle 5 also causing the handle to move in a clockwise direction about its pivotal connection with frame 3 until it assumes the indicating "tripped" position intermediate the "on" and "off" positions, as shown in Figure 6. As the actuating lever 17 rotates, the extension 13 thereof carries the movable contact carrier 48 outwardly within the slots 46 and 47 to move the movable contact fingers 51 away from the fixed contacts. As may be seen from Figure 6, as a result of these movements, the ears 9 of the spring lever 8 are engaged by the ears 10 of the overload lever 22.

After the alloy has sufficiently cooled so that the ratchet wheel 28 is no longer rotatable, the parts may be returned to the manual control. This is effected by rotating handle 5 from the position of Figure 6 in a clockwise direction whereby the ears 9 of spring lever 8, engaging the ears 10 of overload lever 22, force lever 22 to rotate in a counterclockwise direction about its pivot in the frame. As this movement is effected, the latch 24 is moved downwardly from the position of Figure 6 past the ratchet wheel

23, so that when handle 5 is released, latch 24 will move slightly upward to engage one of the teeth of ratchet wheel 23. The latch 24 is then held by the ratchet wheel 23 in the position illustrated in Figure 5, which also shows the position of the other parts after this resetting operation has been effected. The switch may then again be manually operated as described above, until further overload occurs.

It will be seen that the device of the present invention is both sturdy and reliable and operates with a quick make and a quick break action. It will further be seen that the device is trip-free. In addition, the structural arrangement providing for snapping on and off of the terminal-contact members 24, and the "snap" on connection of cover 39, together with the free sliding mounting of the movable contact carrier 48 makes the device inexpensive to assemble, and provides for ready accessibility to both the fixed and the movable contacts whereby they may be easily changed or cleaned as the occasion arises.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. In an electric switch having actuating means operable to effect opening and closing of an electrical circuit through the switch, movable contact means operable by said actuating means to open and closed circuit positions, an insulating base enclosing said actuating and movable contact means, conducting fixed contact means of substantially resilient metal and generally U-shape disposed at opposite sides of said base with the opposing leg portions of said fixed contact means tightly engaging upper and lower surfaces of said base whereby said fixed contact means are held in position by the resiliency of said fixed contact means, and a generally U-shaped cover of insulating material disposed about said fixed contact means, upstanding portions of said cover spaced apart a distance substantially equal to the width of said base, and interengaging distorted portions on said upstanding portions and said base whereby said cover is mounted to said base only by the resiliency of said cover.

2. In an electric switch having actuating means operable to effect opening and closing of an electrical circuit through the switch, movable contact means operable by said actuating means to open and closed circuit positions, an insulating base enclosing said actuating and movable contact means, conducting fixed contact means of substantially resilient metal and generally U-shape disposed at opposite sides of said base, an electrical contact mounted to one leg of said U, terminal means in the other leg of said U, the opposing leg portions of said fixed contact means tightly engaging upper and lower surfaces of said base whereby said fixed contact means are held in position by the resiliency of said fixed contact means, and a generally U-shaped cover of insulating material disposed about said fixed contact means, upstanding portions of said cover spaced apart a distance substantially equal to the width of said base, and interengaging distorted portions on said upstanding portions and said base whereby said

cover is mounted to said base only by the resiliency of said cover.

3. In an electric switch having actuating means operable to effect opening and closing of an electrical circuit through the switch, movable contact means operable by said actuating means to open and closed circuit positions, an insulating base enclosing said actuating and movable contact means, one portion of said base having side walls and an open bottom, a pair of spaced insulating barriers within said base portion paralleling said side walls and dividing said base portion into three chambers, slots extending through said barriers, said movable contact means being guided for rectilinear movement by said slots as said actuating means are operated, conducting fixed contact means of substantially resilient metal and generally U shape disposed at opposite sides of said base, the opposing leg portions of said fixed contact means tightly engaging upper and lower surfaces of said base whereby said fixed contact means are held in position by the resiliency of said fixed contact means, and a generally U-shaped cover of insulating material disposed about said fixed contact means, upstanding portions of said cover spaced apart a distance substantially equal to the width of said base, and interengaging distorted portions on said upstanding portions and said base whereby said cover is mounted to said base only by the resiliency of said cover.

4. In an electric switch having actuating means operable to effect opening and closing of an electrical circuit through the switch, an insulating base having side walls and at least a portion having an open bottom, a pair of spaced insulating barriers within said base portion paralleling said side walls and dividing said base portion into three chambers, slots extending through said barriers, movable contact means within said slots comprising a carrier with spaced contacts thereon, each of said contacts extending into a separate chamber, means operated by said actuating means for moving said movable contact means to open and closed circuit positions, and fixed contact means of substantially resilient metal and generally U shape disposed at opposite sides of said base, one of the legs of said U tightly engaging an upper surface of said base while the other leg tightly engages a lower surface of said base whereby said fixed contact means are positioned on said base by the resiliency of said fixed contact means.

5. In an electric switch having actuating means operable to effect opening and closing of an electrical circuit through the switch, an insulating base having side walls and at least a portion having an open bottom, a pair of spaced insulating barriers within said base portion paralleling said side walls and dividing said base portion into three chambers, slots extending through said barriers, movable contact means within said slots comprising a carrier with spaced contacts thereon, each of said contacts extending into a separate chamber, means operated by said actuating means for moving said movable contact means to open and closed circuit positions, fixed contact means of generally U shape disposed at opposite sides of said base, one of the legs of said U tightly engaging an upper surface of said base while the other leg tightly engages a lower surface of said base whereby said fixed contact means are positioned on said base by the resiliency of said fixed contact means, and a U-shaped cover of insulating material disposed

about said fixed contact means, said cover having legs spaced apart a distance substantially equal to the width of said base, and interlocking portions on said legs and base whereby said cover is mounted to said base only by the resiliency of said cover.

6. In an electric switch having actuating means operable to effect opening and closing of an electrical circuit through the switch, an insulating base having side walls and at least a portion having an open bottom, a pair of spaced insulating barriers within said base portion paralleling said side walls and dividing said base portion into three chambers, slots extending through said barriers, movable contact means within said slots comprising a carrier with spaced contacts thereon, each of said contacts extending into a separate chamber, means operated by said actuating means for moving said movable contact means to open and closed circuit positions, and fixed contact means of generally U shape disposed at opposite sides of said base, an electrical contact mounted to one leg of said U, terminal means mounted to the other leg of said U, the terminal carrying leg tightly engaging an upper surface of said base while the other leg tightly engages a lower surface of said base, and interlocking portions on at least one of the legs and on the base whereby said fixed contact means are positioned on said base by the resiliency of said fixed contact means.

7. In an electric switch having actuating means operable to effect opening and closing of an electrical circuit through the switch, an insulating base having side walls and at least a portion having an open bottom, a pair of spaced insulating barriers within said base portions paralleling said side walls and dividing said base portion into three chambers, slots extending through said barriers, movable contact means within said slots comprising a carrier with spaced contacts thereon, each of said contacts extending into a separate chamber, means operated by said actuating means for moving said movable contact means to open and closed circuit positions, fixed contact means of generally U shape disposed at opposite sides of said base, an electrical contact mounted to one leg of said U, terminal means mounted to the other leg of said U, the terminal carrying leg tightly engaging an upper surface of said base while the other leg tightly engages a lower surface of said base whereby said fixed contact means are positioned on said base by the resiliency of said fixed contact means, a U-shaped cover of insulating material disposed about said fixed contact means, said cover having legs spaced apart a distance substantially equal to the width of said base, and interlocking portions on the interior of said legs and the base whereby said cover is mounted to said base only by the resiliency of said cover.

8. In an electric switch, an insulating base, a frame, an operating handle pivoted in said frame, a first lever pivoted in said frame and in said handle, an overload lever pivoted in said frame, an actuating lever pivoted in said overload lever, an operating spring interconnecting said first lever and said actuating lever, and thermal responsive means normally holding said overload lever in a predetermined position, movement of said first lever by movement of said handle effecting movement of said spring across the pivotal connection between the actuating and overload levers whereby said actuating lever is rotated, and contact means operated by said actuating lever to open and close the electrical circuit through the switch.

9. In an electric switch, an insulating base, a frame, an operating handle pivoted in said frame, a first lever pivoted in said frame, a pin and slot connection between said handle and said first lever, an overload lever pivoted in said frame, an actuating lever pivoted in said overload lever, an operating spring interconnecting said first lever and said actuating lever, and thermal responsive means normally holding said overload lever in a predetermined position, movement of said first lever by movement of said spring across the pivotal connection between the actuating and overload levers whereby said actuating lever is rotated, and contact means operated by said actuating lever to open and close the electrical circuit through the switch.

10. In an electric switch, an insulating base, a frame, an operating handle pivoted in said frame, a first lever pivoted in said frame, a slot in said handle, a pin on one end of said first lever cooperating with said handle slot whereby rotation of said handle effects rotation of said first lever, an overload lever pivoted in said frame, an actuating lever pivoted in said overload lever, an operating spring connected to the opposite end of said first lever and to said actuating lever, thermal responsive means, and means on said overload lever normally engaging said thermal responsive means whereby said overload lever is retained in a predetermined position with the pivotal connection of said actuating lever therein substantially in alignment with the pivotal connection of said first lever in said frame, rotation of said handle in a first direction effecting rotation of said first lever in the opposite direction whereby said spring is moved across the pivotal connection of the actuating lever in the overload lever and thereby effects rotation of the actuating lever, and contact means operated by said actuating lever to open and close the electrical circuit through the switch.

11. In an electrical switch, an insulating base, a frame, an operating handle pivoted in said frame, a first lever pivoted in said frame, a slot in said handle, a pin on one end of said lever cooperating with said handle slot whereby rotation of said handle effects rotation of said first lever, an overload lever pivoted in said frame, an actuating lever pivoted in said overload lever, an operating spring connected to the opposite end of said first lever and to said actuating lever, and means responsive to overload current flow through said switch for normally retaining said overload lever in a predetermined position, said last mentioned means releasing said overload lever in response to overload current flow whereby said overload lever is rotated in said frame and carries the pivot of said actuating lever across said operating spring to effect a rapid pivotal movement of said actuating lever, and contact means moved by said actuating lever to open circuit position.

12. In an electric switch, an insulating base, a frame, an operating handle pivoted in said frame, a first lever pivoted in said frame and in said handle, an overload lever pivoted in said frame, an actuating lever pivoted in said overload lever, an operating spring interconnecting said first lever and said actuating lever, and thermal responsive means normally holding said overload lever in a predetermined position, movement of said first lever by movement of said handle effecting movement of said spring across the pivotal connection between the actuating and overload levers whereby said actuating lever is rotated, and contact means operated by said actuating lever to open and close the electrical circuit through the switch.

connection between the actuating and overload levers whereby said actuating lever is rotated, fixed contacts, and movable contact means for cooperation therewith comprising an insulating plate with movable contacts mounted thereto, said actuating lever effecting movement of said movable contacts toward and away from said fixed contacts.

13. In an electric switch, an insulating base, a frame, an operating handle pivoted in said frame, a first lever pivoted in said frame and in said handle, an overload lever pivoted in said frame, an actuating lever pivoted in said overload lever, an operating spring interconnecting said first lever and said actuating lever, and thermal responsive means normally holding said overload lever in a predetermined position, movement of said first lever by movement of said handle effecting movement of said spring across the pivotal connection between the actuating and overload levers whereby said actuating lever is rotated, spaced fixed contacts, movable contact means for cooperation therewith comprising an insulating plate having spaced contacts thereon, and slots within said insulating base guiding said insulating plate for rectilinear movement, said actuating lever having a lost motion connection to said plate for effecting movement of said plate within said slots to open and close the electrical circuit through the switch.

14. In an electric switch, an insulating base, a frame, an operating handle pivoted in said frame, a first lever pivoted in said frame and in said handle, an overload lever pivoted in said frame, an actuating lever pivoted in said overload lever, an operating spring interconnecting said first lever and said actuating lever, and thermal responsive means normally holding said overload lever in a predetermined position, movement of said first lever by movement of said handle effecting movement of said spring across the pivotal connection between the actuating and overload levers whereby said actuating lever is rotated, fixed contact means of generally U shape disposed at opposite sides of said base, the opposing leg portions of said fixed contact means tightly engaging upper and lower surfaces of said base whereby said fixed contact means are held in position by the resiliency of said fixed contact means, movable contact means for cooperation therewith comprising an insulating plate having spaced contacts thereon, and slots within said insulating base in which said insulating plate operates, said actuating lever effecting movement of said plate within said slots to open and close the electrical circuit through the switch.

15. In an electric switch, an insulating base, a frame, an operating handle pivoted in said frame, a first lever pivoted in said frame and in said handle, an overload lever pivoted in said frame, an actuating lever pivoted in said overload lever, an operating spring interconnecting said first lever and said actuating lever, and thermal responsive means normally holding said overload lever in a predetermined position, movement of said first lever by movement of said handle effecting movement of said spring across the pivotal connection between the actuating and overload levers whereby said actuating lever is rotated, fixed contact means of generally U shape disposed at opposite sides of said base, an electrical contact mounted to one leg of said U, terminal means in the other leg of said U, the opposing leg portions of said fixed contact means tightly engag-

ing upper and lower surfaces of said base whereby said fixed contact means are held in position by the resiliency of said fixed contact means, movable contact means for cooperation therewith comprising an insulating plate having spaced contacts thereon, and slots within said insulating base guiding said insulating plate for rectilinear movement toward and away from the stationary contacts, said actuating lever having a sliding connection to said plate for effecting movement of said plate within said slots to open and close the electrical circuit through the switch.

16. In an electric switch, an insulating base, a frame, an operating handle pivoted in said frame, a first lever pivoted in said frame and in said handle, an overload lever pivoted in said frame, an actuating lever pivoted in said overload lever, an operating spring interconnecting said first lever and said actuating lever, and thermal responsive means normally holding said overload lever in a predetermined position, movement of said first lever by movement of said handle effecting movement of said spring across the pivotal connection between the actuating and overload levers whereby said actuating lever is rotated, fixed contact means of generally U shape disposed at opposite sides of said base, an electrical contact mounted to one leg of said U, terminal means in the other leg of said U, the opposing leg portions of said fixed contact means tightly engaging upper and lower surfaces of said base whereby said fixed contact means are held in position by the resiliency of said fixed contact means, movable contact means for cooperation therewith comprising an insulating plate having spaced contacts thereon, slots within said insulating base in which said insulating plate operates, said actuating lever effecting movement of said plate within said slots to open and close the electrical circuit through the switch, and a generally U-shaped cover of insulating material disposed about said fixed contact means, said cover having upstanding portions spaced apart a distance substantially equal to the width of said base and interlocking with the base whereby said cover is mounted to said base only by the resiliency of said cover.

17. In an electric switch having actuating means operable to effect opening and closing of an electrical circuit through the switch, movable contact means operable by said actuating means to open and closed circuit positions, an insulating base enclosing said actuating and movable contact means, one portion of said base having side walls and an open bottom, conducting fixed contact means of generally U shape, an electrical contact mounted to one leg of said U, a threaded hole and distorted portions in the other leg of said U, a screw in said threaded hole, a distorted portion in said base on the top of said side walls cooperating with said leg distorted portion and a portion of said side wall adjacent said open bottom engaging said one leg of said U, whereby said fixed contact means are mounted to said base by the inherent resiliency of said fixed contact means.
